CLAIM

I claim the ornamental design for a purse, as shown.

DESCRIPTION

FIG. 1 is a front perspective view of a purse showing my new ornamental design;

FIG. 2 is a front elevated view thereof;

FIG. 3 is a side view thereof;

FIG. 4 is a top view thereof;

FIG. 5 is a bottom view thereof;

FIG. 6 is a rear elevated view thereof;

FIG. 7 is a front perspective view of a purse according to an alternative embodiment of my new ornamental design;

FIG. 8 is a front elevated view thereof;

FIG. 9 is a side view thereof;

FIG. 10 is a top view thereof;

FIG. 11 is a bottom view thereof; and,

FIG. 12 is a rear elevated view of the front thereof.
